UNITED STATES PATENT OFFICE.

JOHN K. CHAMP, OF PARIS, KENTUCKY.

BOLT-HEAD HOLDER.

1,099,426.

Specification of Letters Patent.

Patented June 9, 1914.

Application filed August 12, 1913. Serial No. 784,385.

To all whom it may concern:

Be it known that I, JOHN K. CHAMP, a citizen of the United States, residing at Paris, in the county of Bourbon and State 5 of Kentucky, have invented certain new and useful Improvements in Bolt-Head Holders; and I do hereby declare the following to be a full, clear, and exact description of the invention, such as will enable others skilled 10 in the art to which it appertains to make and use the same.

My invention relates to improvements in bolt head holders and has particular reference to that type which are designed for 15 holding a round head bolt to prevent its turning during the operation of removing the nut therefrom.

An important object of my invention is to provide a device of the above mentioned 20 character which employs a plurality of co-acting teeth in connection and formed integral with the jaws of pliers or a wrench.

A further important object of my invention is to provide a device of the above 25 mentioned character which is constructed of few parts reliable in its operation and cheap to manufacture.

The above and additional objects are accomplished by such means as are illustrated 30 in the accompanying drawings, described in the following specification, and then more particularly pointed out in the claim which is appended hereto and forms a part of this application.

With reference to the drawings wherein 35 I have illustrated the preferred embodiment of my invention as it is reduced to practice, and throughout the several views of which similar reference numerals designate 40 corresponding parts, Figure 1 is a side elevation of my device as used in connection with pliers, Fig. 2 is a vertical sectional view taken on line 2—2 of Fig. 1, illustrating the teeth forming a part of my invention, Fig. 45 3 is a plan view of my device illustrating it in connection with a wrench, and Fig. 4 is a longitudinal vertical section taken on line 3—3 of Fig. 3.

Referring to the drawing forming a part 50 of this specification and in which like numerals are employed to designate corresponding parts, the numerals 1 and 2 designate the handles of the pair of pliers, each provided with jaws 3 and 4 respectively as 55 will be clearly seen with reference to Fig. 1. Each of the jaws 3 and 4 is provided

upon one of its side faces with a plurality of substantially V-shaped teeth 5. The teeth 5 are fixed integral with the jaws in spaced relationship and the pointed ends thereof 60 extend beyond the edges of the jaw faces to provide for gripping engagement with the head of the bolt not shown. The jaws 3 and 4 are provided with arcuately recessed and corrugated surfaces 6 which assist the 65 teeth 5 in gripping the bolt by gripping the head of the bolt while the teeth 5 are arranged to grip the bolt shank, thus securely holding the bolt against rotation. An auxiliary lever or handle 7 is pivotally mounted 70 as indicated at 8 to the handle 1, to provide for the closing of the jaws 3 and 4 when the jaws are to engage a bolt of such size as would ordinarily cause the handles 1 and 2 to move apart such a distance as would 75 prevent the operator from grasping the two handles with one hand. The pointed ends of the teeth 5 are corrugated as indicated at 9 to provide the positive gripping engagement of the teeth with the bolt head. 80

It is apparent that my device will positively hold the bolt head to provide the desired action in a manner which has been previously described, and that various uses of my device may be had in shop work for 85 unscrewing nuts, holding pins of various types and other obvious uses.

With reference to Figs. 3 and 4 in which is illustrated a modified form of my invention, the numerals 10 and 11 designate a 90 fixed and sliding jaw respectively of a wrench designated 12 as an entirety. The jaws 10 and 11 are each provided with a plurality of teeth 13 formed integral with the jaws upon one of the side faces. The 95 teeth 13 are constructed after the same manner as the teeth 5 in my preferred form, and the pointed edges thereof extend beyond the jaw faces of each of the jaws. The jaws 10 and 11 are provided with arcuately recessed and corrugated gripping surfaces 14 adapted to receive the head of a bolt. The sliding jaw 11 is operated by means of a screw threaded adjusting bar 15, and the manner of operating the jaws 10 and 11 to provide for their engagement with a bolt head is similar to that described in connection with my device as illustrated in Figs. 1 and 2.

The form of my invention illustrated in 110 Figs. 3 and 4 is best adapted for heavy work as it is obvious that a better gripping en-

gagement of the jaws 10 and 11 is facilitated by means of the construction illustrated in the above mentioned figures.

In reduction to practice I have found that the form of my invention illustrated in the drawings and referred to in the above description as the preferred embodiment, is the most efficient and practical; yet realizing that the conditions concurrent with the adoption of my device will necessarily vary, I desire to emphasize the fact that various minor changes in details of construction, proportion, and arrangement of parts may be resorted to, when required, without sacrificing any of the advantages of my invention, as defined in the appended claim.

Having thus described my invention what is claimed is:

A bolt holder comprising co-operating gripping jaws, each of said jaws being provided upon their inner faces with arcuately recessed and corrugated gripping surfaces formed intermediate of the faces of the jaws and adapted to receive a bolt head, and a plurality of integral spaced and approximately V-shaped teeth formed upon one side of each of said jaws and having their apex edges disposed approximately flush with the inner faces of the jaws. 20 25

In testimony whereof I affix my signature 30 in presence of two witnesses.

JOHN K. CHAMP.
